SELF-ALIGNING ROTARY KILN

Samuel W. Traylor, Jr., Allentown, Pa.

Application December 22, 1948, Serial No. 66,730

13 Claims. (CL 308—203)

1

This invention relates to new and useful improvements in rotary kilns, coolers and driers. More particularly, the present invention relates to new and useful improvements in self-aligning support structures for such equipment.

In conventional type rotary kilns and like equipment having the usual riding rings it is the practice to rotationally support the kilns by means of roller supports which are engaged by the riding rings on the kilns. Frequently these rotary kilns become misaligned due to warping or twisting of the kilns and when this occurs the problem is presented of providing adequate support for the equipment so that undue stresses in the kiln are eliminated during operation thereof.

With this in mind, the principal object of the present invention is to provide a novel roller support construction for the riding rings of rotary kilns and the like which is operable automatically to provide adequate support for the kiln at all times under conditions of horizontal and vertical misalignment due to longitudinal warping or twisting of the kiln.

Another object of the invention is to provide a novel roller support construction as set forth which is operable to support its designed share of the weight of the kiln irrespective of the degree of misalignment or warped condition of the kiln.

Another object of the present invention is to provide a novel roller support construction having the features and advantages set forth which is of relatively simplified construction, comparatively inexpensive to manufacture and maintain, and which is highly efficient and fool-proof in use and operation.

These and other objects of the invention and the various features and details of the construction and operation thereof are hereinafter fully set forth and described with reference to the accompanying drawings in which:

Fig. 1 is a view in section transversely through a rotary kiln showing a riding ring thereon and roller supports for the kiln, made according to the present invention;

Fig. 2 is an enlarged elevational view of one of said roller supports a portion of which has been broken away to illustrate certain structural details thereof;

Fig. 3 is a view along line 3—3; Fig. 2;

Fig. 4 is a sectional view taken on line 4—4; Fig. 2;

Fig. 5 is a sectional view taken on line 5—5; Fig. 2;

Figs. 6 to 13 inclusive are schematic views illus-

2

trating the operation of the roller supports of the present invention when the warp of the kiln is vertically disposed; and

Fig. 14 is a schematic illustration showing the operation of the roller supports of the present invention when the warp of the kiln is horizontally disposed.

Referring now more particularly to the drawings, the present invention is shown in conjunction with a conventional type rotary kiln 1 having the usual riding rings 2 secured circumferentially thereof. In accordance with customary practice the kiln 1 is rotatably supported by means of pairs of relatively spaced roller supports which are associated with each riding ring 2. The roller supports may be employed in unitary assemblies mounted upon suitable bed plates 3 secured upon a foundation or base structure 4, for example, of concrete.

20 Each roller support comprises a cradle 5. This cradle 5 is mounted for limited pivotal movement in the generally angular position shown. At its lower or inner end the cradle 5 is pivotally supported by means of aligned relatively spaced apart rollers 6 which are seated in substantially complementary semicircular grooves 7 and 8 provided respectively in the cradle 5 and the inclined portion of a support 9 which is secured upon the bed plate 3. At its outer or upper end the cradle 5 normally rests upon and is supported by the upper end of a cylinder 10 which provides an unyielding seat for the cradle outer end. The cylinder 10 is pivotally supported at its lower end by means of relatively spaced aligned rollers 11 seated in correspondingly configured recesses 12 and 13 provided respectively in the cylinder member 10 and a support 14 likewise secured to the bed plate 3.

Intermediate the supports for the cradle 5 provided by the rollers 6 and the cylinder 10, the cradle 5 is provided with a generally semi-circular well or recess 19 in which is seated a bearing member generally designated 20, and the lateral wall portions of the recess 19 are constructed and arranged, as indicated at 21 to provide substantially semi-circular seats or supports for the laterally projecting trunnion portions 22 of the bearing member 20. The bearing member 20 is of hollow, relatively heavy construction and intermediate its trunnion portions 22 it is provided with an enlarged portion 23 which is the section of a sphere constructed and arranged, for example, as described in my copending application for United States Letters Patent, Serial No. 55 50,747, filed September 23, 1948.

The spherical section 23 of the bearing 20 is surfaced with a suitable bearing metal 24 and rotatably mounted thereon is a support roller 25 which comprises an outer annular tire member 26 and a pair of internal annular supporting rings 27 constructed and arranged as described in the aforesaid patent application. The bearing member 20 may be cooled, for example, by water introduced therein by means of a pipe 28 having an upwardly directed discharge nozzle 29. The overflow water from the bearing passes through a pipe 30 and is discharged into the cradle 5 where it cools the tire 26 and ultimately drains off through a pipe 31. Suitable lubrication of the bearing surface 24 may be accomplished by discharging a selected lubricant through a pipe 32.

As previously stated the outer or upper end of the cradle 5 is adapted normally to rest upon and be supported by the upper end of the cylinder 10. However, in order that the support roller 25 may move upwardly and remain in supporting contact with its associated riding ring 2 in the event of misalignment of the kiln due to warping or twisting thereof, there is provided in the cylinder 10 a piston 33 which is urged in the upward direction within the cylinder by means of hydraulic fluid maintained under a predetermined pressure. Pivotal contact between the upper end of the piston 33 and the outer end of the cradle 5 is provided by means of a roller 34 which is seated in correspondingly configurated recesses 35 and 36 provided respectively in the underside of the outer end of the cradle 5 and the upper end face of the piston 33.

In accordance with the present invention the piston 33 in the cylinder 10 is actuated upwardly by introducing into the cylinder through a pipe 37, a suitable hydraulic fluid such as, for example, oil under pressure. The hydraulic fluid acting on the piston 33 is maintained at or under a predetermined uniform pressure by means of the use of a suitable accumulator 38 such as, for example, of the well-known Greer type. Connected to the accumulator 38 through a valve 39 is an oil or other hydraulic fluid reservoir 40. Associated with the reservoir 40 is a hand pump which is operated, for example, once or twice yearly to replace fluid which may escape or leak from the hydraulic system depending upon the efficiency of the fit between the piston 33 and cylinder 10.

In accordance with the present invention the hydraulic fluid acting on the piston 33 is maintained under a predetermined uniform pressure by the accumulator 38 so that the upward force or lift exerted by the said piston 33 upon the cradle 5 is equal, for example, to approximately 95% or 98% of the portion of the weight of the kiln which normally is borne by the cylinder 10. Consequently, and as previously pointed out, when the kiln 1 is in perfect alignment the cradle 5 rests upon and is supported by the upper end of the cylinder 10. However, in the event that the kiln becomes warped or twisted so that it is no longer in perfect alignment and a particular riding ring 2 tends to be lifted out of supporting engagement with its support roller 25 in the normal position of the latter, the hydraulic fluid in the cylinder 10 will cause the piston 33 likewise to move upwardly and maintain the roller 25 in engagement with the ring 2 with the result that said roller 25 continues to support, for example, 95% or 98% of its normal share of the weight of the kiln.

In further illustration of the foregoing operation, and with reference to Figs. 6 and 7 of the

drawings, there is shown a warped kiln provided with three riding rings 2 and a like number of roller supports therefor. In Fig. 6 the warp is downward in the center of the kiln but the center 5 roller support structure can not be displaced downwardly because its cradles 5 are supported directly upon the unyielding upper ends of the cylinders 10. At the ends of the kiln, however, where the warp of the kiln is in an upward direction away from the normal position of the endwise rollers 25, the hydraulic force acting on the piston 33, for example, being approximately 95% of the normal load, operates to move the endwise pistons 33 upwardly so that the associated rollers 25 are maintained in supporting contact with the endwise riding rings 2 of the kiln and continue to bear their fair share of the load.

With reference to Fig. 7 the kiln 1 has been rotated 180° from the piston shown in Fig. 6 20 and just the reverse situation exists. In this position the warp of the kiln is downward at the ends and upward in the middle, the endwise rollers 25 and cradles 5 are seated directly on the unyielding upper ends of the cylinders 10 and 25 the intermediate support structure has been actuated upwardly by the pressure fluid acting on the piston 33 to maintain its roller 25 in supporting contact with the intermediate riding ring 2. The percentage of the normal kiln weight borne by 30 the roller supports associated with each riding ring 2 are given for a 95% counter loading of the pistons 33. Figs. 8 to 13 inclusive, of the drawings, illustrate other possible warp conditions frequently encountered in kilns having a plurality of 35 longitudinally spaced riding rings 2 and roller supports therefor, and in each instance the approximate percentage of normal weight load borne by each support likewise is given for a 95% counter-loading of the pistons 33.

40 With reference to Fig. 14 of the drawings, there is illustrated the manner in which the kiln is supported when the warp of the kiln is disposed horizontally or in other words following a quarter revolution of the kiln from the vertical warp 45 position shown, for example, in Fig. 13. Thus the right-hand roller 25 moves inwardly to maintain supporting contact with the riding ring 2 and provide, for example, approximately 95% of normal support to the kiln while the other or 50 left-hand roller is slightly over-loaded and supports approximately 105% of the normal load. After a further quarter turn the position of the kiln rotationally will be as in Fig. 12 so that both the right and left-hand rollers of each pair will 55 carry the same or 100% of their normal load and with still another quarter turn the loadings on the rollers will be reversed from that shown in Fig. 14 so that the right-hand roller is over loaded and supports about 105% of the normal 60 load while the left-hand roller supports about 95% of the normal load.

65 From the foregoing description it will be observed that the present invention provides a novel roller support construction for the riding rings of rotary kilns which is operable automatically to provide at all times adequate support for the kiln under conditions of both horizontal and vertical misalignment due to longitudinal warping or twisting of the kiln. The invention 70 also provides a novel roller support construction which is operable to support at all times a fair share of the weight of the kiln irrespective of the misalignment or warped condition of the kiln. The invention further provides a roller support construction for kilns having the fea-

tures and advantages set forth which is characterized by its relatively simplified construction, comparative low cost of manufacture and maintenance and which is highly efficient and fool-proof in operation and use.

While a particular embodiment of the invention has been illustrated and described herein, it is not intended to limit the invention to such disclosure and changes and modifications may be made therein and thereto within the scope of the following claims.

I claim:

1. In a rotary kiln including a shell having a series of riding rings thereon, rollers to support each ring, a pivoted support for each roller, a member providing an unyielding seat on which said pivot support is adapted normally to rest, and power means acting continuously on said pivoted support in a direction to unseat the same and exerting a force thereon slightly less than the load normally borne by said unyielding seat member.

2. In a rotary kiln including a shell having a series of riding rings thereon, rollers to support each ring, a pivoted support for each roller, a member providing an unyielding seat on which said pivoted support is adapted normally to rest, and hydraulic operated means acting continuously on said pivoted support in a direction to unseat the same and exerting a force thereon slightly less than the load normally borne by said unyielding seat member.

3. In a rotary kiln including a shell having a series of riding rings thereon, rollers to support each ring, a pivoted support for each roller, a cylinder providing an unyielding seat on which said pivoted support is adapted normally to rest, and hydraulic operated piston means in said cylinder acting continuously on said pivoted support in a direction to unseat the same and exerting a force thereon slightly less than the load normally borne by said cylinder.

4. In a rotary kiln including a cylindrical shell having a series of circumferential riding rings thereon, a pair of relatively spaced rollers to support each ring, a support for each roller disposed transversely of the shell and mounted for pivotal movement toward and away from said ring, a member disposed normally to be engaged by and provide an unyielding seat for said pivoted support, and a hydraulic ram acting continuously on said pivoted support in a direction to unseat the same.

5. In a rotary kiln including a cylindrical shell having a series of circumferential riding rings thereon, a pair of relatively spaced rollers to support each ring, a support for each roller disposed transversely of the shell and mounted for pivotal movement toward and away from the shell, a cylinder disposed normally to be engaged by and provide an unyielding seat for said pivoted support, a piston in said cylinder, and hydraulic means acting continuously on said piston in the direction of said support, said hydraulic means being under a predetermined uniform pressure calculated to exert on the support a force slightly less than the load normally borne by said cylinder.

6. In a rotary kiln including a cylindrical shell having a series of circumferential riding rings thereon, a pair of relatively spaced rollers to support each ring, a bearing for each roller, a support for each bearing disposed transversely of the shell and mounted for pivotal movement toward and away from the shell, a cylinder disposed normally to be engaged by and provide an un-

yielding seat for said support, a piston in said cylinder, and hydraulic means acting continuously on said piston in the direction of the support, said hydraulic means being under a predetermined uniform pressure calculated to exert on the support a force slightly less than the load normally borne by said cylinder.

7. In a rotary kiln including a cylindrical shell having a series of circumferential riding rings thereon, a pair of relatively spaced rollers to support each ring, a support for each roller disposed transversely of the shell and mounted for pivotal movement toward and away from the shell, a cylinder disposed normally to be engaged by and provide an unyielding seat for said support, a piston in said cylinder, means providing rolling engagement between said piston and support, and hydraulic means acting continuously on said piston in the direction of the support, said hydraulic means being under a predetermined uniform pressure calculated to exert on the support a force slightly less than the load normally borne by said cylinder.

8. In a rotary kiln including a cylindrical shell having a series of circumferential riding rings thereon, a pair of relatively spaced rollers to support each ring, a bearing for each roller, a support for each bearing disposed transversely of the shell and mounted for pivotal movement toward and away from the shell, a cylinder disposed normally to be engaged by and provide an unyielding seat for said support, a piston in said cylinder, means providing pivotal engagement between said piston and support, and hydraulic means acting continuously on said piston in the direction of the support, said hydraulic means being under a predetermined uniform pressure calculated to exert on the piston a force slightly less than the load normally borne by said cylinder.

9. In a rotary kiln including a cylindrical shell having a series of circumferential riding rings thereon, a pair of supporting cradles disposed in association with each riding ring transversely of the shell at the opposite sides of the axis thereof and mounted for pivotal movement toward and away from said ring, a member providing an unyielding seat for each cradle on which the latter is adapted normally to rest, a roller support rotationally mounted in said cradle and engaging the periphery of the riding ring, and power operated means acting continuously on said cradle in a direction to unseat the same and exerting thereon a force slightly less than the load normally borne by said unyielding seat member.

10. In a rotary kiln including a cylindrical shell having a series of circumferential riding rings thereon, a pair of supporting cradles disposed in association with each riding ring transversely of the shell at the opposite sides of the axis thereof and mounted for pivotal movement toward and away from said ring, a member providing an unyielding seat for each cradle on which the latter is adapted normally to rest, a bearing member in said cradle, a roller support journaled on said bearing and engaging the periphery of said ring, and a hydraulic ram acting continuously on said cradle in a direction to unseat the same and exerting thereon force slightly less than the load normally borne by said unyielding seat member.

11. In a rotary kiln including a cylindrical shell having a series of circumferential riding rings thereon, a pair of supporting cradles disposed in

association with each riding ring transversely of the shell at the opposite sides of the axis thereof and mounted for pivotal movement toward and away from said ring, a cylinder providing an unyielding seat for each cradle on which the latter is adapted normally to rest, a roller support mounted in said cradle and engaging the periphery of said ring, a piston in said cylinder engaging said cradle, and hydraulic means acting continuously on said piston in the direction of the cradle under a predetermined uniform pressure calculated to exert on the cradle a force slightly less than the load normally borne by said cylinder.

12. In a rotary kiln including a cylindrical shell having a series of circumferential riding rings thereon, a pair of supporting cradles disposed in association with each riding ring transversely of the shell at the opposite sides of the axis thereof and mounted for pivotal movement toward and away from said ring, a cylinder providing an unyielding seat for each cradle on which the latter is adapted normally to rest, a bearing member mounted in said cradle, a roller support journaled on said bearing and engaging the periphery of said ring, a piston in said cylinder engaging said cradle, and hydraulic means acting continuously on said piston in the direction of the cradle under a predetermined uniform pressure calculated to exert on the cradle a force slightly less than the load normally borne by said cylinder.

13. In a rotary kiln including a cylindrical shell

5
10

having a series of circumferential riding rings thereon, a pair of supporting cradles disposed in association with each riding ring transversely of the shell at the opposite sides of the axis thereof and mounted for pivotal movement toward and away from said ring, a cylinder providing an unyielding seat for each cradle on which the latter is adapted normally to rest, a non-rotatable bearing member having opposite end portions mounted in said cradle and having an enlarged intermediate bearing portion provided with a surface the section of a sphere, a roller support journaled on said spherical bearing portion and engaging the periphery of said ring, a piston in said cylinder engaging said cradle, and hydraulic means acting continuously on said piston in the direction of the cradle under a predetermined uniform pressure calculated to exert on the cradle a force slightly less than the load normally borne by said cylinder.
